(57) **CLAIM**

The ornamental design for a cleaning cloth, as shown and described.

DESCRIPTION

FIG. 1 is a bottom plan view of a cleaning cloth in accordance with the new design;

FIG. 2 is a top plan view thereof; and,

FIG. 3 is a bottom perspective view thereof in a crumpled state.

The broken lines in FIG. 1-3 are for the purpose of illustrating portions of the cleaning cloth that form no part of the claimed design.

1 Claim, 3 Drawing Sheets
